FIREARM

Peter B. Rutherford, Herkimer, N. Y., and Kenneth J. Lowe, deceased, late of Ilion, N. Y., by Jane A. Lowe, administratrix, Ilion, N. Y., assignors to Remington Arms Company, Inc., Bridgeport, Conn., a corporation of Delaware.

Application August 27, 1947, Serial No. 770,774

11 Claims. (Cl. 42—16)

1

This invention relates to a safety mechanism for a firearm and more particularly to such a mechanism designed to lock the trigger against movement to a firing position.

It is a principal object of this invention to present a safety mechanism which is well adapted to low cost quantity production and one which, although achieving its low cost objective, has done so without sacrificing positiveness of action or other desirable functional qualities.

It is a further object of this invention to present a simple reliable safety which will positively prevent firing of the rifle from an unlocked bolt.

It is an object of a modified form of the invention to present a safety mechanism fulfilling the objects previously mentioned and which is, in addition, capable of being automatically set to "Safe" condition whenever the firearm is cocked.

It is contemplated that these objectives may best be attained by rotatably mounting on the rear end of the bolt a trigger block carrying member which can be located in various rotationally separated positions allowing for predetermined degrees of trigger movement.

The exact nature of the invention, as well as other objects and advantages thereof, will appear from consideration of the following specification referring to the attached drawings in which:

Figure 1 is a side elevational view, partly in section, showing the working elements of the fire-arm.

Figure 2 is a longitudinal sectional view of the same mechanism included in Figure 1.

Figure 3 is a partial rear elevational view, the bolt being closed and the mechanism in "Safe" position.

Figure 4 is a partial cross-sectional view on the line 4—4 of Figure 2, the bolt being closed as in Figure 3 but the mechanism being set in "Firing" position.

Figure 5 is a partial cross-sectional view, corresponding to Figure 4, with the exception that the bolt is shown in an unlocked position and the safety in "Safe" position.

Figure 6 is a partial cross-sectional view corresponding to Figure 4, with the exception that the bolt is shown in an unlocked position and the safety in "Firing" position.

Figure 7 is a side elevational view of the bolt body showing the detent opening therein.

Figure 8 is a rear elevational view, similar to Figure 3, showing a modified mechanism designed to automatically apply the safety when the bolt is unlocked. In this view the bolt is closed and the safety is in "Firing" position.

2

Figure 9 is a partial cross-sectional view, corresponding to Figure 8, with the bolt in unlocked position and the safety shifted to "Safe" position.

Figure 10 is a partial cross-sectional view, similar to Figure 9, the bolt having been returned to closed position, carrying with it the safety in "Safe" position.

Figure 11 is a partial side elevational view of the modified mechanism.

10 Referring to the drawings by characters of reference, there is shown a firearm comprising a stock 1 and a tubular receiver 3 mounting a barrel in usual fashion at its front end and suitably assembled to a stock. A breech bolt 4 of the upturn and pullback type is provided with a handle 5 and a locking lug 6 cooperating with the usual locking recess and guide track in the receiver. At its chamber closing end, the breech bolt is provided with a conventional extractor and conventional spring loaded ejector plunger, it being noted that because of the one-piece nature of the bolt, a clearance cut is provided in the rear face of the barrel adjacent the chamber opening to permit the extractor to be rotated with the bolt relative to the barrel.

15 The bolt 4 is longitudinally bored to accept a striker 7 and has a slightly offset reduced bore to accept the firing pin 8 integrally secured to the striker. The striker is provided with an undercut flange 9 to act as a sear-engaging surface. A clearance slot is provided in the bolt to accept the sear nose 10 of the trigger. In view of the fact that the whole bolt body rotates relative to the receiver, the rear portion of the clearance slot 20 must be carried around the circumference of the bolt through the same angle as the upturn of the bolt. From the edge of this clearance slot adjacent the sear nose when the bolt has been rotated to unlocked position, a slot may be carried 25 forward to accept the sear nose during the pull-back movement of the bolt. The forward terminal end of this slot is adapted to be engaged by the forwardly facing surface 11 of the sear nose, which also acts as a bolt stop. In the usual fashion, the pulling of the trigger to an extreme rearward position when the bolt has been pulled to the rear disengages the sear nose from the slot and permits the bolt to be withdrawn.

20 The trigger 12 is pivotally supported on a crosspin 13 in the receiver and a rearwardly extending arm thereon bears against a spring 14 which, at its other end, bears against a detent plunger 15. It is the function of the plunger to engage a notch 16 formed in the bolt body to prevent inadvertent opening of the bolt. This

detent also exerts enough frictional resistance to pulling back the bolt, when the trigger is pulled to clear the bolt stop, that there is little possibility of the bolt inadvertently falling clear and possibly picking up dirt or other foreign material.

Within the bolt body a main spring 17 bears at its forward end on the striker and at its rearward end on the inner surface of the safety 18. The safety is a caplike member suitably knurled to provide a secure gripping surface and received on the reduced rear portion of the bolt body. As seen in Figure 7, the bolt body is provided with a detent slot 19 providing two semi-circular forwardly facing detent notches 20 and 21. This slot receives the reduced end of a detent screw 22 radially positioned in the safety and by reason of the engagement of the main spring against the inner face of the safety the screw will bear against the rear face of the slot. In this way, the mainspring is retained and provides the spring force holding the safety detent into one or the other of the notches 20 or 21.

Formed on the safety body is a segmental flange adapted to engage and limit the movement of a rearwardly extending arm 23 on the trigger. The segment 24 has a great enough radial dimension that it prevents the movement of the trigger to striker releasing position when the safety is set to "Safe" position (Figure 3). Circumferentially, the segment 24 extends far enough to so oppose the trigger arm during the entire turning movement of the bolt, in which the safety participates by reason of its engagement in the detent notch in the bolt body. See Figure 5 for the relative position of safety and trigger with the bolt unlocked.

When the safety has been rotated on the bolt body to its other or "Firing" position and the bolt is closed as in Figure 4, the segment 25 opposes the trigger arm 23. The maximum radial height of the segment 25 is such as to just permit the sear to disengage from the striker and the minimum radial height is that which will permit an undesirable amount of overtravel or "slap" in the trigger. For best performance, this height should be as near the maximum as the probable accumulation of production tolerances will permit.

With the safety set in "Firing" position, it will be apparent that rotation of the bolt toward an unlocked position will carry with it the safety and the segment 26 to oppose the trigger arm 23. This segment is of the same radial height as the segment 24 and consequently blocks striker releasing movement of the trigger. Figure 6 shows the relationship of the parts with the bolt rotated to completely unlocked position and the safety in "Firing" position.

It is desirable to adjust any trigger mechanism for a short clean releasing movement, but such an adjustment offers a possible hazard of "jar-off" if the bolt is carelessly handled or "slammed" shut. Regardless of the position of the safety, the construction presented here is of great assistance in overcoming this danger for the trigger is positively blocked from jarring out of engagement until substantially the entire locking surface of the receiver recess is opposed to the bolt locking lug.

To make the condition of the safety instantly apparent to the user, a white enamel or lacquer-filled notch 27 on the safety is correlated with a green-filled notch 28 on the bolt, indicating

"Safe" condition, and a red-filled notch 29 on the bolt, indicating "Firing" condition.

The safety shown herein can be conveniently utilized with either the single shot construction shown or with equivalent types of magazine rifles.

It will be noted that the action of moving the safety to "Firing" position involves a counter-clockwise rotation of the safety which can be facilitated by a slight forward pressure. For a right-handed shooter, the usual method of operation will be to grasp the safety between the right thumb and forefinger and the movement to "Firing" position will land the thumb in the appropriate position to grasp the stock without fumbling or lost motion. If an opportunity for a shot is lost and it is desired to switch back to "Safe" position, the thumb will ordinarily be in position to be immediately closed upon the safety.

The modified safety mechanism shown in Figs. 8 to 10 is particularly desirable for a single shot rifle, since it causes the safety to be automatically applied whenever the bolt is rotated to unlocked position. The result is that each time the rifle is loaded, the safety will be applied without requiring any conscious action on the part of the user, and the rifle cannot be fired without consciously releasing the safety. Since single shot rifles are often purchased for boys, who by reputation may tend to be careless of details, the value of this type of safety will be obvious.

Referring to the drawings, it will be seen that the modified mechanism is of generally similar construction to that previously illustrated herein. Reference numerals between 100 and 129 have been applied to parts which are the same or exact equivalents to those in the earlier modification. Reference numerals between 50 and 100 have been used to designate those parts different from those previously discussed.

As previously described, the safety 118 forms a closure for the rear end of the bolt 104 and is thrust rearwardly thereon by the main spring 117. The thrust of the main spring is resisted by the detent screw 122 received in slot 119 in the bolt and releasably engaged with either notch 120 or 121. A notch 127 on the safety correlates with notches 128 and 129 on the bolt body to afford an instantaneous indication of the condition of the rifle.

The principal change to the rifle in the modified form has been the provision of a pin 50 mounted in the rear end face of the receiver 103 which engages with the flange 51 on the safety when an attempt is made to open the bolt with the safety in "Firing" position and resists the normal tendency of the safety to turn with the bolt. The result is that when the bolt is rotated to unlocked position, the safety is shifted to "Safe" position on the bolt unless it already occupies that position. In "Safe" position with the bolt locked, a segment 52 of the flange opposes the arm 123 on the trigger to block release of the sear nose 110 from the flange 109, as shown in Fig. 10.

In "Firing" position, with the bolt locked, shown in Fig. 8, a segment 53 of less radial height serves as a trigger stop to prevent undesirable overtravel of the trigger. A flange 54 is provided on the bolt in position to block the trigger before the bolt can be rotated to a degree which causes a dangerously reduced area of the

bolt lug 106 to be opposed by the wall of the bolt locking recess.

As previously pointed out, the rotation of the bolt to unlocked position shifts the safety to "Safe" position. When the bolt is rotated back to locked position, the safety is unopposed by the stop pin on the bolt and is therefore free to follow its natural inclination to rotate with the bolt by reason of the interengagement of the screw 122 in the appropriate detent notch in the bolt. During the initial phase of the rotation to closed position, the trigger arm 123 is opposed by the segmental flange 54 on the bolt body. From a point in advance of that in which the bolt reaches a locked position, in which it is releasably retained by the detent 115, the segment 52 of the safety flange takes over the trigger blocking function to insure that at no time during the final closing movement of the bolt can the striker be jarred off from the sear.

The same push-in and turn movement is utilized to operate this safety as in the previous modification.

Although two more or less specific embodiments have been disclosed herein, it is not intended that the invention should be considered to be limited thereby. The invention is considered to extend to all equivalent constructions within the scope of the claims appended hereto.

We claim:

1. In a firearm including a receiver, an upturn and pullback bolt in said receiver having rotationally separated locked and unlocked positions, a striker within said bolt, a spring within said bolt in engagement with said striker to urge same forwardly in said bolt, and a trigger mounted in said receiver and provided with sear means engageable with the striker to releasably hold same in a cocked position against the urging of said spring; safety means comprising in combination an element extending from the trigger and provided with a blocking surface, a member rotatable on said bolt between a "Safe" position and a "Firing" position thereon, detent means engageable between said member and said bolt to releasably retain the member in the selected one of said positions on the bolt, flange means on said member formed to define at least one segmental abutment which is opposed to said blocking surface when said member is set in "Safe" position and said bolt is in locked position, said abutment being of sufficient radial height to positively prevent movement of the trigger to striker releasing position and of sufficient circumferential extent that the abutment will continue to block the trigger as the bolt is rotated from locked position toward unlocked position.

2. Safety means as described in claim 1, said member having a second segmental abutment formed on said flange means and positioned in opposition to said blocking surface when the member is in "Firing" position to permit limited movement of said element for release of the striker but to prevent material overtravel thereof.

3. Safety means as described in claim 2, said member having a third segmental abutment formed on said flange means and positioned in movement blocking opposition to the blocking surface on said element when the bolt has been materially moved away from locked position and said member is in "Firing" position, said first-mentioned abutment being constructed and arranged to be in movement blocking opposition

to the blocking surface on said element when said member is in "Safe" position when the bolt has been moved from locked position as well as when the bolt is in locked position.

4. Safety means as described in claim 1, said member engaging the rear end of the bolt to form a cap-like closure therefor.

5. Safety means as described in claim 4, the inner surface of said member being in abutting relation to the rear end of the striker spring to serve as a stop therefor.

6. Safety means as described in claim 5, said bolt being provided with a cross slot and said member being retained on said bolt against the action of the striker spring by a stop in the member extending into the slot.

7. Safety means as described in claim 6, forwardly facing circumferentially spaced detent notches being formed in the rear edge of said cross slot for selective engagement with said stop, said notches being circumferentially spaced in accordance with the separation between "Safe" and "Firing" positions.

8. In a firearm including a receiver, a bolt rotatable in said receiver to a locked position therein, a striker in said bolt, a trigger, and a sear controlled by said trigger and operable to releasably retain the striker in a cocked position; safety means comprising in combination a segmental flange integral with said bolt constructed and arranged to be rotated therewith into engagement with a portion of said trigger to prevent movement of the sear to striker releasing position whenever the bolt has been rotated materially away from its locked position in said receiver, a manual safety member rotatably mounted on the bolt and arranged to be selectively positioned in rotationally separated "Safe" and "Firing" positions, and an abutment on said manual safety member arranged with the bolt in locked position to be opposed to a portion of the trigger to prevent movement of the sear to striker releasing position when the member is in "Safe" position and clear of said trigger portion to permit movement thereof when the member is in "Firing" position.

9. Safety means for a firearm including in addition to those defined in claim 8 detent means engaged between the bolt and said member, releasably retaining the member in a pre-set position, and a stop surface on said receiver in opposition to the said abutment on said member, the abutment and said stop surface being constructed and arranged to engage each other and prevent said member from rotating with the bolt when the bolt is rotated to an unlocked position with said member in "Firing" position, whereby said member will be shifted automatically to "Safe" position as an incident to rotation of the bolt to unlocked position.

10. Safety means for a firearm including in addition to those defined in claim 9 a second abutment on said member positioned in opposition to a portion of the trigger when the member is in "Firing" position, said second abutment being constructed and arranged not to engage the said portion of said trigger before the trigger has moved to striker releasing position and serving as a trigger stop to prevent material overtravel thereof.

11. Safety means for a firearm as defined in claim 10, said member having the general form of

a cap secured on the rear end of said bolt to serve as a closure therefor.

PETER B. RUTHERFORD.
